UNITED STATES PATENT OFFICE.

JOHN J. McANDREWS, OF SAN DIEGO, CALIFORNIA.

TUBE CLEANER.

Application filed December 12, 1922. Serial No. 606,466.

To all whom it may concern:

Be it known that I, JOHN J. McANDREWS, a citizen of the United States, and a resident of San Diego, in the county of San Diego and State of California, have invented a new and Improved Tube Cleaner, of which the following is a full, clear, and exact description.

This invention relates to cleaning devices for steam boilers and has for an object to provide an improved construction for blowing the soot from either a water tube boiler or fire tube boiler wherein the cleaning operation may be carried on efficiently without interrupting the use of the boiler.

Another object of the invention is to provide a cleaning device for boiler tubes wherein one or more sets of jets are arranged to blow into the tubes at different times while the boiler is in use, the arrangement being such that all of the tubes may be cleaned in a minimum time.

A further object of the invention is to provide a cleaning apparatus for boilers wherein jets of steam under pressure are directed into the tubes not only of the boiler but of the air heating device associated therewith so that all of the tubes through which the flame or smoke passes may be quickly and readily cleaned at any time.

A still further object of the invention is to provide a cleaning apparatus for boiler tubes which may be left in place continually and at desired times brought into operative position so as to clean out successively the tubes in groups.

In the accompanying drawings—

Figure 1 is a longitudinal vertical sectional view through a boiler showing a cleaner embodying the invention applied thereto.

Figure 2 is a transverse sectional view through Figure 1 approximately on line 2—2, the same showing the arrangement of certain parts of the cleaner.

Figure 3 is a side elevation partly in section of the lower end of one set of cleaning tubes and associated parts, the same being on an enlarged scale.

Figure 4 is a top plan view of the structure shown in Figure 3.

Figure 5 is a bottom plan view of the rack shown in Figure 3.

Figure 6 is an enlarged fragmentary sectional view through one of the jets shown

in Figure 1 together with a section of the supply pipe carrying the same.

Referring to the accompanying drawings by numerals, 11 indicates a boiler which may be of any type but which in the drawing is shown as a fire tube boiler. As is well known, this boiler is provided with a number of tubes 12 of usual construction and also with a number of large tubes 13. Arranged in the smokestack or draft member 14 is a device 15 acting as a heater for heating the air used in the fire box 16. The heater 15 is provided with a number of tubes 17 similar to tubes 12 and, consequently, accumulating soot to a greater or less extent so that they need be cleaned at desirable intervals and according to the present invention, means have been provided for cleaning the same simultaneously with cleaning the tubes 12.

In constructing the cleaner embodying the invention, a number of variations may be used without departing from the spirit of the invention, certain variations being desirable in different kinds of boilers. In the boiler shown in the accompanying drawings, preferably there are arranged three sets of tubes 18 and 19; said sets for the purpose of description may be known as A, B and C. Each of the tubes 18 and 19 act as a header or supply pipe for steam for a number of jets 20 which may be of any desired kind but preferably of the type shown in Figure 6. It will be noted from Figure 6 that the bore of the nozzle or jet 20 tapers from the end 21 to a central point 22 and then flares outwardly to the outer end 23.

This particular form of nozzle is intended to give the desired velocity to the steam as it strikes or rather as it enters the various tubes 12 whereby the tubes will be filled with steam and, consequently, the soot will be quickly blown therefrom. By flaring the outer part of the bore of the nozzle, the steam does not enter the tubes 12 in a small stream and gradually spread somewhere in the tube but is expanded until the jet of steam is about of the same diameter as the bore of the tubes 12 as the same enters said tubes. This will cause the tubes to be thoroughly cleaned quickly. It will be noted that the respective pipes 18 and 19 extend vertically so as to take in at one time one set or vertical series of tubes 12 and to clean all of these tubes at one time.

105
110

When the first vertical row or series of tubes 12 have been cleaned, the pipes 18 and 19 and each of the groups or sets A, B and C are moved over to the next set or series of 5 vertical rows and the operation repeated. This action is continued until all of the rows for each group or set of tubes 18 and 19 have been cleaned.

It will be noted from Figure 2 that by 10 reason of the fact that the headers 18 and 19 are both connected with the same base 24, which is hollow, these two headers will be moved simultaneously and, consequently, there will be two vertical rows of tubes 12 15 cleaned at the same time. As indicated in Figure 3, the base 24 is secured to a rack bar 25 by any suitable means, as for instance, straps 26, said rack bar having a centrally positioned rack 27 and depending 20 side rails 28 and 29 adapted to rest on the various rollers 30. The base 24 is provided with a stuffing box 31 through which a pipe 32 extends and in which it is slidingly fitted so that the base 24 may be telescoped 25 thereover as the headers 18 and 19 of group or set A move from the position shown in Figure 2 toward the right. The pipe 32 is connected to a supply pipe 33 and may be supplied with steam therefrom whenever the 30 valve 34 is opened. The rack 25 is provided with a few apertures 35 registering with suitable apertures in the base 24 so that small jets of steam may be projected downwardly therethrough for cleaning the rack 35 27 and associated parts including the driving pinion 36. This driving pinion continually meshes with rack 27 and is supported by a shaft 37 which is journaled in the angle bar 38 and the channel iron 39. 40 This angle bar and channel iron, together with the rollers 30 and associated parts, make what is substantially a track for the base 24 and the rack bar 25 whereby it may travel freely back and forth and perform 45 its functions as desired.

In order that the base 24 may not leave the rollers 30 or swing the same, a plate 40 acting as a retaining bracket is rigidly secured by bolts or otherwise to the channel 50 iron 39 and overlaps the rack bar 25. This rack bar is, therefore, prevented from rising upwardly and is prevented from moving outwardly away from the bar by reason of the various anti-friction rollers 41 journaled in the channel iron 39. The shaft 37 extends not only through the channel iron 39 but also outwardly and through the lower part of the hood 14 where a suitable crank 55 42 is mounted so that as this crank is rotated, shaft 37 will be rotated and, consequently, the set or section A will be moved. The sets or sections B and C are constructed 60 identically with set A and are operated identically so that no further description 65 will be necessary, said sets, however, being

preferably actuated by independent cranks 42 so that there will only be two headers working at a time:

As indicated in Figure 2, there are division plates or sheets 43 and 44 forming part 70 of the smoke box 14 whereby by reason of the independent operation of the various sections A, B and C, these will not prevent an efficient operation of the device. In case the device should be used on a boiler 75 where these plates are not provided, the operation will be the same. Arranged near the upper end of the smoke box 14 are pipes or rods 45 and 46 which extend preferably entirely across the end of the boiler so as 80 to act as a guide for the various sections A, B and C and to prevent any appreciable outward or inward swinging of the headers 18 and 19. Preferably, each of these headers is provided with a horizontal auxiliary 85 header 47 provided with suitable nozzles 20 so that as the various headers move from one set of tubes 12 to the other, the auxiliary header 47 will move from one set of tubes 17 to the other and thereby clean 90 these tubes simultaneously with the cleaning of tubes 12. It is, of course, evident that if the heating device 15 is not used, the auxiliary header could be eliminated.

In most steam boilers, a set of large tubes 95 13 are provided and in order to clean these tubes, a fixed or stationary pipe 48 is positioned substantially as shown in Figure 1 and suitable nozzles mounted therein positioned to direct the steam into both sets of 100 tubes. This is a permanent fixture and the steam may be turned on and off at any time. When the device is not in use, the various headers are moved to one side of the tubes or as much out of the way as possible and 105 left in place but the steam is, of course, turned off. As positioned, the headers will not effect a proper draft but will always be in position for use at any time. Where certain grades of oil are used to heat the 110 boiler, more or less soot is deposited and, consequently, it is desirable to clean the tubes rather often in order to maintain the efficiency of the boiler. From this it will be evident that it is important to have the 115 parts in position for use at any time. In order that the operator may know the position of the various headers when the device is in use, a dial 49 is secured to the smoke box or to some other stationary part and 120 a pointer 50 secured to the respective shafts 37. The pointer and dial are so positioned and positioned in respect to the headers and the boiler that the operator may easily know where the headers are located and whether or not they are directly in front 125 of the various tubes.

What I claim is:—

1. A boiler tube cleaner, comprising a plurality of sets of headers, a plurality of 130

nozzles carried by each header, a hollow base connected with the lower ends of said headers, a supply steam pipe extending into one end of said base, there being a sliding 5 connection between the supply steam pipe and the base, means for moving the base transversely of the boiler, a fixed plate overlapping part of the base for preventing the base from leaving its normal position and 10 swinging outwardly, and a rod co-acting with the upper end of said headers for preventing the headers from swinging away from said boiler at the upper end.

2. A cleaner for boiler tubes, comprising a 15 plurality of headers, a plurality of nozzles carried by each of the headers, means for supplying steam to said headers, a rack connected with said headers, a gear associated with said rack, means for rotating said gear 20 so as to move said headers from one set of tubes to another, a plurality of supporting rollers for said rack and headers, and means for preventing lateral moving of said headers, said means including a plurality of 25 rollers and a retaining bracket.

3. In a cleaner for tubes of steam boilers, a header, a plurality of nozzles carried by said header, a hollow base carrying said header, means for supplying steam to said 30 base while allowing the base to move trans-

versely of the boiler, a rack secured to said base, a pinion meshing with said rack, a shaft secured to said pinion, means for rotating said shaft, a track including a pair of members supporting said shaft, a plurality 35 of rollers carried by said members and engaging part of said base for supporting the same, a plurality of vertically arranged rollers for preventing lateral moving of said base, and means for preventing the base 40 from moving off of the first mentioned rollers while moving thereover.

4. In a boiler tube cleaner, a header, comprising a base, a rack of substantially the same length as the header rigidly secured to 45 the under surface thereof, a stationary steam supply tube extending into said header, means surrounding said tube and carried by said base for providing a tight connection as the base moves back and forth over said tube, a fixed rotatable pinion meshing with said rack, vertically and horizontally arranged rollers for supporting and guiding said rack, means for rotating said pinion, and a stationary fixed plate overlapping 50 part of said rack for preventing the same from leaving said pinion and also preventing said header from moving outwardly at the bottom.

JOHN J. McANDREWS.
